SPOOL-GRIPPER CARPET LOOM

William Felton, Bradford, England, assignor to
 David Crabtree & Son Limited, Bradford, England, a British company

Application May 13, 1950, Serial No. 161,832
 In Great Britain August 17, 1949

1 Claim. (Cl. 139—7)

1

This invention relates to spool-gripper carpet looms.

Spool-gripper carpet looms have chains which carry a series of frames having mounted on them, spools carrying the pile yarn, and combs which guide and lightly grip the ends of pile yarn individually in order to present the extremities of the ends to the grippers which operate by gripping the extremities of the ends presented to them and then drawing enough length of the ends through the comb whilst the spool frame is held momentarily in its active position by a holding device to provide the desired pile tufts which are then severed from the ends so as to leave sufficient yarn projecting from the comb to enable the ends to be gripped on the next presentation of the said ends to the grippers.

In order to ensure that the correct length of pile tuft is severed and that a clear severance takes place, the ends must be kept in tension. Hitherto this tension was obtained by a continuously acting, spring loaded brake block pressing on the periphery of one flange of each spool. If the frictional resistance of the brake block to rotation of the spool is sufficiently strong to produce sufficient yarn tension to obtain the correct tuft length, a clean severance and the correct amount of projecting yarn for next production of tufts therefrom, the yarn gradually slips backwards through the comb, because it is elongated and tightened on the spool during the drawing thereof from the spool and thereafter gradually returns to its normal length and slackness on the spool, and therefore at the next presentation of the ends to the grippers there is insufficient yarn projecting to enable the grippers to grip it or the length of yarn engaged in the grippers is reduced and therefore the tuft is shorter. As different ends stretch differently and are gripped with different degrees of tightness by the comb, this backward slipping takes place irregularly and gives rise to tuftless points and a ragged pile surface.

The object of the said invention is to ensure that the ends shall always be present in correct length of projection of their extremities from the comb when the grippers operate to grip them, whilst also ensuring that the yarn shall be in tension whilst it is being drawn through the comb and is having a tuft length cut off it.

A spool-gripper carpet loom according to the said invention has a spool brake or brakes which exert a braking effect on the spools intermittently and thus leave the spools free to rotate and thereby give off yarn to compensate for the yarn shrinkage in length and slackening on the spools

2

which occur between successive removals of tuft lengths from the spools.

The said spool brake or brakes may be operated by a mechanism which acts synchronously with the spool-frame holding device to apply the brakes for each period of operation of the holding device and release the brake or brakes at the end of each period of operation.

The said spool brake or brakes may be mounted on a stationary part of the loom and act successively on the spool or spools of each spool frame when it is in its active position.

The brake operating mechanism may be actuated by a link rod pivotally mounted on an oscillatable arm forming part of the spool-frame holding device and connected by a second arm to a shaft having a third arm which is pivotally connected by a second rod to one end of a bell crank lever or levers pivotally mounted on a stationary part and having a brake surface provided at the other end.

There are as many levers as there are spools in each spool-frame and where the number of levers exceeds one, a spring is provided in the connection between each lever and the second rod to compensate for any differences in amounts of movement of the levers required to brake the spools.

The brake or brakes preferably operate on one flange of each spool.

In addition to the intermittently acting brake or brakes, a constantly acting brake may be provided on each spool frame for each spool, the resistance of the constant brakes to rotation of the spools being less than the resistance of the comb to slipping of the yarn therethrough and therefore not preventing rotation of the spools to compensate for the yarn shrinkage in length and slackening on the spool, but however being sufficient to prevent undesirable slackness of the yarn between the spools and the combs due to the weight of the yarn or vibration by preventing rotation of the spools by the weight of the yarn between the spools and the comb or by vibration in the intervals between the control of the spools by the intermittently acting brake or brakes.

I attain the said object by the mechanism illustrated in the accompanying drawings, wherein—

Figure 1 is a fragmentary front elevation of a spool brake mechanism of a spool-gripper carpet loom;

Figure 2 is a front elevation of a portion of the mechanism illustrated in Figure 1 and is drawn to a larger scale; and

Figure 3 is a side view, regarded in the direc-

tion of the arrow 3, of the mechanism illustrated in Figure 1, and is drawn to the same scale as Figure 2.

Referring to the drawings, wherein some known parts are indicated in dot-and-dash lines, a construction is shown therein as applied by way of example to a spool-gripper carpet loom in which each spool frame 1 has a spool 2 and a spool 3 rotatably mounted on it and is held temporarily arrested in its active position by a holding arm 4 which clamps it to a locating block 5 and is mounted on an operating shaft 6 actuated mechanically at the correct moments. A brake operating arm 4' is provided on the operating shaft 6 and has an elongated slot 7 and a pivotal stud 8 parallel with the operating shaft 6 is mounted adjustably along the slot 7. An upwardly extending link rod 9 is connected to the brake operating arm 4' by an end piece 10 mounted on the pivot stud 8. The upper end of the link rod 9 is connected to one end of an arm 11 by means of an end piece 12 and a pivot pin 13 engaging the end piece 12 and arm 11 and situated horizontally but at right angles to the pivot stud 8.

The arm 11 is secured on one end of a short shaft 14 mounted in a stationary bearing 15 and having secured at its other end an arm 16 projecting upwardly and at right angles to the arm 11, the shaft 14 being parallel with the pivot pin 13. The arm 16 has a link rod 17 connected to it pivotally by means of an end piece 18 on the rod and a pivot pin 19 which is parallel with the shaft 14.

The link rod 17 extends horizontally into the space between the sides of the spool-frame chains (not shown) and the lower chain wheels 31 provided to guide the said chains at the locality where the frames arrive in the active position.

A bell-crank lever 20 is mounted on a pivot stud 22 carried by a stationary part of the loom, the pivot stud 22 being parallel with the shaft 14. The lever 20 has an upwardly projecting arm 24 the upper end of which has a fork 26 open at the upper end and slidably engaged by the link rod 17. The lever 20 also has an arm 28 which is at an angle to the arm 24 and is also bent laterally to clear a shaft 30 on which the chain wheels 31 are mounted.

A bell-crank lever 21 is mounted on a pivot stud 23 carried by a stationary part of the loom, the pivot stud 23 being parallel with the shaft 14. The lever 21 has an upwardly projecting arm 25 the upper end of which has a fork 27 open at the upper end and slidably engaged by the link rod 17. The lever 21 also has an arm 29 which is at an angle to the arm 25 and is also bent laterally to clear the shaft 30.

The end of the arm 28 registers with a flange 32 of the spool 2 of each spool-frame 1 and the end of the arm 29 registers with a flange 33 of the spool 3 of the same spool frame 1 when the respective spool frame 1 is in its active position. The end of the arm 28 has a brake block 34 adapted to be pressed against the periphery of the spool flange 32. The end of the arm 29 has a brake block 35 adapted to be pressed against the periphery of the spool flange 33.

For the arm 24 of the lever 20, there is on the link rod 17 a fixed but adjustable collar 36 which acts to hold the brake block 34 clear and a fixed but adjustable collar 38 which acts on the fork 26 in reverse direction through a helical compression spring 40 provided on the rod 17 be-

tween the collar 38 and the fork 26 and presses the fork 26 towards the collar 36.

For the arm 25 of the lever 21, there is on the link rod 17 a fixed but adjustable collar 37 which acts to hold the brake block 35 clear, and a fixed but adjustable collar 39 which acts on the fork 27 in reverse direction through a helical compression spring 41 on the rod 17 between the collar 39 and the fork 27 and presses the fork 27 towards the collar 37.

In operation, as the holding arm 4 is moved by its operating shaft 6 into the spool-frame clamping position, the link rod 9 is driven upwards by the brake operating arm 4' and rocks the shaft 14 by means of the arm 11 thereon. The shaft 14 rocks the arm 16 thereon and thereby pushes the link rod 17 in the said reverse direction. The collars 38, 39 on the rod 17 act through the compression springs 40, 41 on the bell crank levers 20, 21 and rotate them until their brake blocks 34, 35 are pressed against the spool rims 32 and 33 respectively with pressures dependent on the strength of the springs 40, 41. If one brake block, for example the brake block 34, makes contact with the flange 32 of the spool 2 before the brake block 35 makes contact with the flange 33 of the spool 3, the bell-crank lever 20 is arrested but due to the compression spring 40 interposed between it and the collar 38, it does not prevent continued movement of the rod 17 and therefore the application of the brake block 35 to the flange 33 of the spool 3. Therefore both brake blocks 34 and 35 are applied notwithstanding the presence of small irregularities in one spool position as compared with another or small discrepancies in the diameters of the spool flanges 32 and 33 or the inoperative brake block positions.

When the holding lever 4 is rocked by the operating shaft 6 in reverse direction to release the spool frame 1 after yarn has been drawn and cut therefrom, the link rod 9 is pulled down by the brake operating lever 4' and the collars 36, 37 on the link rod 17 are thereby caused to pull the brake blocks 34 and 35 clear of the spool flanges 32 and 33 respectively.

The brake blocks 34 and 35 therefore hold the spools 2 and 3 strongly against rotation during each period of yarn withdrawal and cutting, but release the spools 2 and 3 immediately after that period and leave them free to rotate until the succeeding period of yarn withdrawal and cutting occurs. Therefore instead of the yarn being drawn between those periods backwards through the comb by shrinkage and slackening on the spool, the spools 2 and 3 rotate to let off more yarn and therefore the positions of the ends are not disturbed at the comb between the said periods and the extremities of the ends thereof are always available to the grippers and the length of the tuft pieces is substantially constant.

Light spring brakes (not shown) may without detriment be provided on each frame to act on flanges of the spools in order to prevent the pull created by the weight of the yarn or vibration from unwinding the yarn from the spools and thereby forming between the spools and the combs yarn loops liable to become entangled with each other. The spring brakes act continuously as heretofore but have insufficient braking action to prevent rotation of the spools by the stronger pull created by yarn shrinkage and slackening of the coils of yarn on the spools after the tuft pieces have been cut off and the yarn tension created by the pull of the grippers against the

braking action of the intermittently acting brake blocks has therefore ceased.

I claim:

A spool-gripper carpet loom having a spool-braking mechanism comprising an oscillatable arm, a link rod pivotally connected to the said oscillatable arm, a second arm pivotally connected to the link rod, an oscillatable shaft on which the second arm is fixed, a third arm fixed on the said shaft, a second rod pivotally connected to the third arm, an oscillatably mounted bell crank lever operated by the second rod, and a brake surface provided on the said bell crank lever for operation on successive spools of the loom whilst they are in the operative position.
